UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

LAMP CONSTRUCTION.

Application filed March 25, 1925. Serial No. 18,107.

To all whom it may concern:

Be it known that I, CHARLES E. GODLEY, a citizen of the United States, residing at Detroit, in the county of Wayne and State of Michigan, have invented certain new and useful Improvements in a Lamp Construction; and I do hereby declare the following to be a full, clear, and exact description of the invention, such as will enable others skilled in the art to which it appertains to make and use the same.

My invention relates to lamps of the general class in which the body of the lamp casing has a lens-carrying front or cover detachably mounted on it. Generally speaking, my invention aims to provide combined means for latching the lens-carrying front to the casing of such a lamp in a manner affording a yielding and self-adjusting connection between the body of the casing and the said front, for also holding the reflector of the lamp firmly in position when this cover or lamp front is detached, and for permitting a removal of the reflector without detaching any of the latching parts.

In my copending application No. 691,978, filed Feb. 11, 1924, I have shown a construction for this purpose in which the means for effecting the latching and for holding the reflector in its normal position when the cover or lens front is detached include a spring formed of flat material, which spring must be detached from a hook-shaped member to permit the attaching and detaching of the reflector. Since the arrangement there disclosed requires a spring of a width considerably exceeding that of the hook to which it is attached, it also requires a corresponding widening of the lamp body beyond that demanded by the diameter of the reflector. Furthermore, the construction there disclosed requires a partial rotating of the reflector before the latter can be detached. Since this involves an added manipulation to which inexperienced buyers of such lamps are not accustomed, various parts of these lamps (and particularly the reflectors) have sometimes been damaged by the attempts of uniformed users to detach the reflector without giving it the needed preliminary partial rotation. Furthermore, I have found in difficult in practice to secure a uniformity in the bending of the springs required in my

said previous construction, thereby increasing the manufacturing costs.

My present invention aims to overcome all of the above mentioned objections. For this purpose, I provide a construction employing a spring formed of a wire and hence reducing both the cost, the difficulty in securing uniformity of the bending and the needed width of the lamp body, as also reducing the outside diameter of the lens ring correspondingly. I also provide interlocking formations on the reflector and the lamp body which will not require any rotational movement of the reflector either in the detaching of the same from the casing or in attaching the same to the casing, thereby avoiding the difficulties heretofore encountered by inexperienced users and also avoiding such improper manipulations by users as might easily damage the relatively thin reflectors. I also arrange the latching springs so that they may be sprung clear of the reflector, thereby permitting the reflector to be detached or replaced without detaching the springs.

Furthermore, I provide a construction in which both the latching formations on the lens ring and the lens-holding formations are formed on the same integral part of the lens ring, thereby simplifying and cheapening the construction and also avoiding a possible loosening of separately attached latching members in case the manufacture is not carefully watched. Still further and also more detailed objects of my invention will appear from the following specification and from the accompanying drawings, in which—

Fig. 1 is a central, longitudinal and vertical section through an automobile headlight embodying my invention.

Fig. 2 is a front view of the same, with the cover or front member detached.

Fig. 3 is an enlarged and fragmentary section taken along the radial line 3—3 of Fig. 2.

Fig. 4 is a correspondingly enlarged vertical section taken along the line 4—4 of Fig. 2, with the nearer side wall of the lamp body or casing cut away.

Fig. 5 is an enlarged perspective view of a portion of the reflector showing a tongue which engages a corresponding recess in the

flange on the lamp body to prevent rotation of the reflector.

Fig. 6 is a perspective view of one of the springs as it appears when detached.

Fig. 7 is an enlarged front view of a radial outer portion of the lamp body, showing one of the latching springs and the spring support carrying the same, with dotted lines showing how this spring may be sprung out beyond the outer edge of the lamp body to permit the reflector to be attached or detached without bodily removing the spring.

Fig. 8 is a rear view of the cover member which comprises the lens ring and the lens carried by the latter.

Fig. 9 is a view similar to Fig. 4 but with the cover or lens-front of the lamp removed from the casing, showing how the latching spring then directly engages the flange of the reflector.

In the embodiment of the drawings, Fig. 1 shows a section through an automobile lamp in which the body of the casing has a side wall 1 provided at its forward or mouth end with an annular flange 2 against which the outwardly directed flange 3 at the mouth end of the reflector 4 normally bears. The portion of the reflector between this flange 3 and the reflector portion projects forwardly and is provided with a forwardly open groove 5 in which a packing ring 6 is seated. The lamp body also has secured to it a number of spring-latch supports, which are here shown as three in number and as each comprising a base portion 7 secured flatwise to the inner face of the side wall 1 of the lamp body, a stem 8 extending forwardly through a correspondingly formed notch 29 in the inner edge of the flange 2, a rigid tongue 9 disposed in front of the flange 2, and a hook 10 bent from the forward edge of the tongue 9 and curved rearwardly so as to afford a rearwardly directed opening. The tongue 9 also has a perforation 11 for receiving the tail end 12 of a spring 13 which is desirably formed of a resilient wire and which has adjacent to its other end a bight 14 convexed towards the rear of the lamp or towards the flange 2. This spring has an intermediate portion extending into the said hook formation, and this hook formation is so disposed as to cooperate with the socketing of the tail 12 of the spring in the perforation 11 for holding the spring in a position in which its resiliency constantly urges the bight 14 rearwardly or toward the flange 2 of the lamp body.

This body flange 2 is provided at its inner edge with a number of recesses 15 which are here shown as having the aforesaid notches 29 forming radially outward continuations of them. Each of the recesses 15 corresponds substantially in width to a rearwardly directed tongue 16 on the reflector, the tongues 16 being desirably

formed from initial portions of the flange 3 as shown in Fig. 5, so that each tongue 16 normally projects rearwardly beyond the body flange 2 after the manner shown in Fig. 3 and has its ends adapted to engage the ends of the corresponding recess 15 to prevent the reflector from rotating with respect to the lamp body. With the parts thus arranged, the reflector can be inserted or removed freely when the springs 13 are detached, and the subsequent attaching of the springs will cause their brights 14 to engage the forward face of the flange 3 of the reflector to hold the latter in its normal position even before the lens-front or cover of the lamp is attached.

The lens-ring or lens-carrying part of the lens-front is here shown as composed of two substantially annular members both formed of sheet metal. The outer of these has a side wall 17 which is recurved at its rear end to afford a short forwardly directed annular hook formation 18 housing the rear end of a cylindrical flange 19 on the second or inner member of the lens-front. The outer or first named annular member also has an annular front portion 20 carrying an inner and rearwardly directed flange 21 which engages the front of the pane or lens 22. The inner member has an annular flange or shelf portion 23 extending radially inward from its said cylindrical rear portion 19 and connecting the latter to a forwardly directed portion 24 which engages the said frontal portion 20 of the lens ring. Thus arranged, the hook formation 18 at the rear end of the lens ring receives any thrust tending to move the inner part of the latter rearwardly.

The annular shelf 23 of the lens ring is provided with apertures 25 corresponding in number to the springs and their supports. Each aperture 25 is somewhat longer than the distance from the free end of a spring to the opposite end of the tongue 9 of the corresponding spring support, thereby permitting the lens-ring to be attached to the lamp body when the perforations 25 are in approximate alignment with the said tongues and springs. The shelf 23 is provided adjacent to the end of each of its perforations 25 with forwardly directed hump formations 26 over which the bight of the corresponding spring is adapted to ride when the lens front is rotated after it has been slipped into its said alining position. In doing this, the free end of the spring is flexed forwardly, the thickness of the packing 6 being such that the latter through its engagement with the lens of the lamp and through the engagement of the latter with the rigid inner flange 21 of the lens ring will hold the lens ring so far forward as to provide a free spacing of the shelf 23 from the reflector 3. In other words, the spring-

pressed latching arrangement holds the lens front yieldingly and floatingly attached as shown in Fig. 4, allowing the parts to adjust themselves to the thickness and compressibility of the packing ring 6 and enabling this packing to afford a tightly sealing closure for the reflector regardless of variations in the thickness of the lens.

When the lens-ring or lamp front is in its normal closure position of Fig. 3, the latching springs cooperate with the annular shelf 23 on the lens-ring to urge the latter rearwardly, thereby causing the rearward thrust on the lens as transmitted to the packing ring to press the flange 3 of the reflector firmly against the flange 2 on the lamp body. Likewise, when the lens-front is detached, the same springs 13 engage the reflector directly, as shown in Fig. 9, so as to hold its flange 3 similarly pressed tightly against the flange 2 of the lamp body. Consequently, the reflector is always held in exactly the same position with respect to the lamp bulb 29 regardless of whether or not the lens front is attached to the lamp body, so that the focusing adjustment can readily be made before the lens-front is attached without having the adjustment disturbed by the subsequent attaching of the lens-front.

30 To gain access to the interior of the lamp, the user merely needs to rotate the lens rings sufficiently toward the tail ends of the springs, or towards the left in Fig. 4, to have the free ends of the springs clear the adjacent ends of the perforations 25, after which the lens front can readily be slid off the lamp body.

If the reflector is to be detached, each spring can be pried out of engagement with the corresponding hook 10 on its support by inserting a screw driver between the rear end of this hook formation and the spring, so as to snap the spring out of this hook. Or, each spring may be simply sprung radially outward of the lamp body after the manner shown in dotted lines in Fig. 7, so as to clear the outer edge of the reflector without requiring a detaching of the springs. In practice, I have found that a relatively light gage of wire suffices for such springs, thereby making it easy for both the lamp assembler and the users to distort the springs out of their operative positions in this manner, and also permitting the total width of the springs and spring supports radially of the lamp to be so small as to reduce the diameter of the lens-ring over that required with older types of lamps of the same general class.

60 However, while I have illustrated and described the lamp construction of my invention in an embodiment including desirable shapes, constructions and arrangements of various parts, I do not wish to be limited as to these. Obviously, many changes might

be made as to such features without departing either from the spirit of my invention or from the appended claims.

I claim as my invention:

1. In a lamp, a reflector having a laterally directed flange at its mouth, a forwardly open body housing and supporting the reflector, a spring support secured to the body and having a portion thereof disposed forwardly of the said flange; a wire spring detachably carried by the said portion of the spring support and having a part adapted to engage the flange of the reflector, the spring being also adapted to have its flange-engaging parts swung radially outward of the reflector by a corresponding flexing of the spring, so as to clear the flange and permit the removal of the reflector; the spring support and the spring having interengaging portions preventing a bodily movement of the spring radially outward of the lamp; and a lens-carrying ring having a portion adapted to be slid between the reflector flange and the said engaging portion of the spring upon rotation of the lens-carrying ring with respect to the body, so as to cause the spring to lock the ring to the body.

2. A lamp construction as per claim 1, in which the spring has an end portion extending through the spring support and in which the support has a part engaging another portion of the spring to prevent the withdrawal of the said end portion from the support.

3. A lamp construction as per claim 1, in which the spring support has a perforation therein and a hook formed thereon and spaced from the perforation and open towards the reflector flange; and in which the spring has a portion extending through the said perforation and another portion extending through the hook, whereby the said perforation and hook cooperate in retaining the spring in operative position.

4. A lamp construction as per claim 1, in which the spring support has a perforation therein and a hook formed thereon and spaced from the perforation and open towards the reflector flange; and in which the spring has a portion extending through the said perforation and another portion extending through the hook, whereby the said perforation and hook cooperate in retaining the spring in operative position; the portion of the spring between the hook and the part of the spring which engages the reflector flange being of such a length as to permit this portion to be flexed radially outward of the reflector to dispose the flange-engaging part of the spring beyond the outer edge of the reflector.

5. A lamp construction as per claim 1, in which the reflector and the body having interengaging portions preventing relative rotation thereof and arranged to permit the attaching and detaching of the reflector by

movements longitudinal of the body, and in which the reflector flange has a recess therein opposite the spring support to permit the reflector to be attached or detached by movement longitudinally of the body when the spring is out of its said flange-engaging dis- position.

6. In a lamp, a forwardly open body provided near its mouth with a forwardly 10 facing shoulder, a reflector having at its mouth a flange engaging the forward face of the said shoulder, a rigid spring support secured to the casing behind the said shoulder and extending through the shoulder and

having a portion disposed forwardly of the reflector flange and extending circumferentially of that flange, the said portion having a pair of spring-engageable formations spaced circumferentially of the said flange, and a spring having two spaced parts re- 20 spectively engaged by the said formations and having another part engaging a part of the reflector flange at a distance from the said portion of the spring support.

Signed at Detroit, Michigan, March 20th, 25 1925.

CHARLES E. GODLEY.
